UNITED STATES PATENT OFFICE.

ORVILLE C. LILLIE, OF CONNEAUT, OHIO.

TOOTH-BRUSH.

No. 867,062.

Specification of Letters Patent.

Patented Sept. 24, 1907.

Application filed September 18, 1905. Serial No. 278,871.

To all whom it may concern:

Be it known that I, ORVILLE C. LILLIE, a citizen of the United States, and a resident of Conneaut, county of Ashtabula, and State of Ohio, have invented a new and useful Improvement in Tooth-Brushes, of which the following is a specification, the principle of the invention being herein explained and the best mode in which I have contemplated applying that principle so as to distinguish it from other inventions.

10 My invention relates to improvements in tooth-brushes, and especially to that class of such devices known as rotary tooth-brushes, by the use of which the bristles of the brush, instead of being moved back and forth along the rows of teeth, are drawn along the line 15 of the individual teeth and the crevices between them.

The annexed drawing and the following description set forth in detail certain mechanism embodying the invention, such disclosed means constituting but one of various mechanical forms in which the principle of 20 the invention may be used.

In said annexed drawing, Figure 1 represents a side elevation of my improved rotary tooth-brush, a portion of the handle being broken away to reveal the mechanism for operating the brush; and Fig. 2 represents an 25 axial longitudinal section of the brush, with certain parts, however, shown in elevation.

The essential elements entering into my improved tooth-brush are a handle A, a spindle B mounted within such handle and projecting beyond it at one end, and a 30 rotary brush C secured to such projecting spindle-portion. Associated with the handle is suitable mechanism for rotating such spindle B and attached brush C.

The handle A, as shown, comprises two tubular members a and a', the one within the other, respectively fitting over and within end-rings A' and A², and secured thereto. Detachably secured to end ring A' is a sleeve a² bearing a semi-cylindrical shell a³ that extends along one side of rotary brush C to form a guard by which the mouth and cheeks are shielded from the brush when being rotated in use. Attached in a similar manner to the other end-ring, A², is a sleeve a⁴ bearing a ring a⁵ which both allows the handle A to be more firmly retaining in the hand by forming a sort of thumb rest, and affords a means by which the brush can be readily hung 40 up. Handle members a, a' are further each provided with two oppositely disposed longitudinal slots a⁶, a⁷ respectively; slot a⁶ registering with slot a⁷ as clearly shown in the figures.

Within inner handle member a', as has been already 50 indicated, lies the brush-bearing spindle B. To assure the easy rotation of this spindle it is mounted in ball-bearings. At the one end the balls b are held between a suitably faced flange b' formed on spindle B, and a groove b² formed in end ring A'. At the other end a

ball race is provided by means of a similar groove b² 55 formed in end-ring A² and a cone-faced nut b³ screw-threaded on to the end of spindle B and held against loosening by a set screw b⁴ which serves as a lock-nut. A square screw-thread b⁵ extends along the entire length of that portion of the spindle B which lies within handle A. The portion b⁶ of the spindle that extends beyond the handle is reduced in diameter to receive the brush C. While the manner of attaching the brush to the spindle is immaterial, it should be such that when one brush is worn out it can be readily replaced with a 60 new one.

Slidably mounted upon handle A is a sleeve D, such sleeve being held against rotation thereon by means of inwardly extending lugs or 'teats' d which register in the before described longitudinal slots a⁶, a⁷ in handle members a, a'. The inner ends of these teats are adapted to engage the screw-thread on spindle B, whence it is obvious that motion of sleeve D back and forth along handle A will effect the rotation of spindle B first in one direction, then in the other. Such motion of sleeve 75 D towards one end of the handle is accomplished by means of a helical spring S that surrounds inner handle member a', and lies between outer end-ring A² and lugs d of the sleeve. Outwardly projecting ears or finger pieces d' are attached to sleeve D whereby it can be moved to compress the spring S.

Having thus described the construction of my improved rotary tooth-brush, its manner of operation is readily indicated. The brush is retained in the hand by passing the thumb through ring a⁵ and extending two of the opposed fingers preferably the index and middle finger on opposite sides of the handle A so as to rest against ears d'. Normally the sleeve D with these ears d' is held by spring S in the position shown in both figures, i. e. adjacent to end-ring A'. Upon bringing thumb and fingers together the sleeve will be moved up against the other end ring A², simultaneously effecting the rotation of spindle B by virtue of the engagement of teats d with screw-thread b⁵ on such spindle in the manner already set forth. As is obvious the spring S is at the same time compressed so that immediately upon relieving the pressure on ears d', which is done without withdrawing the fingers therefrom, the sleeve D is returned, under impulse of the expanding spring, to the other end of the handle. This movement produces 90 rotation of the spindle B as before, the direction of rotation being reversed however. While the brush C is thus being rapidly rotated, it may be applied to all parts of the teeth by properly directing handle A within the mouth, guard a³ at the same time protecting the 95 cheeks or tongue, as the case may be, from contact with the bristles. The action of my rotary brush may be made still more effective by having alternate circular

rows of bristle tufts longer than the intermediate ones so as to conform more perfectly with the irregular line presented by the teeth.

Having thus described my invention in detail, that which I particularly point out and distinctly claim is:—

- 5 1. In a rotary tooth brush, the combination of a handle comprising two tubular members, one within the other; a threaded spindle mounted in the inner tubular member and adapted to receive and actuate a rotary brush; a manually operable member slidably mounted in said handle and engaging said threaded spindle; and a spring disposed intermediately of said tubular members and adapted to normally position said slidable member.
- 10 2. In a rotary tooth-brush, the combination of a handle comprising two tubular members, one within the other,

joined at their ends and provided with registering longitudinal slots; a spindle mounted in the inner tubular member and provided with a rotary brush at one end, such spindle being further provided with a screw-thread; a sleeve mounted on the outer tubular member and bearing outwardly-projecting finger-pieces and teats projecting inwardly through said slots into engagement with said screw-thread; and a spiral spring surrounding said inner tubular member and lying between said teats and an abutment at one end of said handle.
